(No Model.)

B. D. McDOWELL.
EGG BEATER.

No. 511,637.

Patented Dec. 26, 1893.

UNITED STATES PATENT OFFICE.

BARTLEY D. McDOWELL, OF MILWAUKEE, WISCONSIN.

EGG-BEATER.

SPECIFICATION forming part of Letters Patent No. 511,637, dated December 26, 1893.

Application filed September 29, 1892. Serial No. 447,294. (No model.)

To all whom it may concern:

Be it known that I, BARTLEY D. McDOWELL, a citizen of the United States, and a resident of Milwaukee, in the county of Milwaukee, and in the State of Wisconsin, have invented certain new and useful Improvements in Stirring or Mixing Utensils; and I do hereby declare that the following is a full, clear, and exact description thereof.

10 My invention relates to new and useful improvements in stirring or mixing utensils for culinary and other purposes and consists in the matters hereinafter described and pointed out in the appended claim.

15 In the accompanying drawings illustrating my invention: Figure 1 is a view partly in elevation and partly in section, of a mixing implement constructed in accordance with my invention. Fig. 2 is a vertical sectional view 20 of the same taken on line 2—2 of Fig. 1. Fig. 3 is a detail sectional view of one of the parts, taken on line 3—3 of Fig. 5. Fig. 4 is a cross sectional view of the same taken on line 4—4 of Fig. 5. Fig. 5 is a top plan view illustrating the construction of the joint between the 25 frame of the mixer and the supporting bracket.

In said drawings A represents a suitable supporting arm upon which the operating parts of the mixer are mounted, this arm being 30 adjustably engaged with a bracket B which is adapted for engagement with the edge of a table or shelf and is provided with a suitable clamping screw b, for securing it thereto. A suitable gear wheel C is journaled upon 35 a spindle c at the outer end of the arm A, and is provided with an operating handle or crank C' by which it may be rotated.

A projection a upon the under side of the arm A, carries a vertically disposed sleeve a' 40 within which is journaled a shaft d carrying at its upper end a pinion D which meshes with the teeth of the gear C, as shown more particularly in Fig. 2.

Rigidly supported at the lower end of the 45 sleeve a' is a gear wheel E, and a suitably shaped frame F is rigidly secured to the lower end of the revolvable shaft d, by means of a suitable key or pin f.

Two stirrers G G, of any desired or convenient form are revolvably supported in the frame F. These stirrers G G, in the particular form of construction shown in the draw-

ings, are made up of any desired number of bars or rods constituting an open work grating or frame. At the top and bottom respectively, of said stirrers are provided spindles g g and g' g', which are journaled in the upper and lower portions of the frame F. Upon the upper ends of the spindles g g are rigidly secured gears G' G' arranged to mesh with the stationary gear E at the lower end of the sleeve a'. It follows from this construction that when the gear wheel C is rotated, motion will be communicated by said gear to the pinion D and shaft d upon which the same is secured. This rotation of the shaft d will obviously cause the frame F secured thereto, to revolve and carry the stirrers G G and the gears G' G' around, and this planetary movement of the gears G' G' will by reason of their engagement with the stationary gear E, cause said gears to revolve upon their own axes which rotation will be transmitted to the stirrers G G in an obvious manner.

The gear E is preferably made of considerably greater diameter than the gears G' G', so that the rotation of the stirrers upon their respective axes will be at a very considerably more rapid rate than the rotation of the frame F upon its axis.

I find it convenient to arrange the arm A so as to be adjustably engaged at its end A', with a projection B' on the supporting bracket B, and to this end, I provide said parts with flat bearing surfaces, and a screw b' is passed 85 centrally through said parts and serves to bind them securely together in their adjusted positions. In order to more securely hold the arm A in its adjusted position, I provide upon one of the flat bearing surfaces suitable 90 radially disposed grooves a² a², and upon the opposite bearing surface of the other part, a radial rib b² adapted for engagement with any desired one of the said grooves a² a². By this construction, the arm A may be readily adjusted upon the bracket B by loosening the screw b' and swinging said arm with the mixer into the desired position, and then turning said screw up so as to bind the arm A to the bracket B in an obvious manner.

In practice I prefer to clamp the bracket B to the edge of a table, shelf or other suitable support, and to support the vessel containing the material to be agitated or mixed in such

a position that the bottom of the frame F will come close to the bottom of said vessel, when the stirrer is in the position illustrated in Fig. 1.

- 5 The arm A may be thrown upward to raise the frame F and the stirrers G G above the level of the vessel, so as to permit it to be placed in proper position, and then moved back into the position shown in the drawings 10 to bring the said frame stirrers down into the vessel. I prefer to provide upon the bottom of the frame F, a point f' projecting downwardly therefrom in the axial line of said frame, and adapted to rest upon the bottom 15 of the vessel to keep the lower side of the said frame from dragging against the bottom of the vessel and also to form a pivotal support upon which said frame rotates.

By my improved construction, the frame F 20 rotating upon its axis, tends to bring the material under treatment toward the center of the vessel, and the independent rotation of the stirrers G G tends to throw the said material toward the outside of the vessel, while 25 by the planetary movement of said stirrers about the axis of the frame F, they are brought into contact with every particle of the material. In this manner, the material under treatment is very thoroughly agitated and the ingredients very intimately mixed together, and 30 the work of stirring or beating, or of mixing ingredients together may be performed in a small fraction of the time usually required

for said operation when performed by hand and with a minimum expenditure of labor. 35

My improved mixing or stirring utensil is adapted for use for a great number of purposes, and I find it exceedingly efficient in all instances where a thorough agitation, aeration, or mixing together of materials is required. 40

Having thus described my invention, what I claim as new, and desire to secure by Letters Patent of the United States, is—

A stirring or mixing utensil comprising a 45 bracket adapted for engagement with a shelf or other support, an arm adjustably engaged with said bracket, a revoluble shaft journaled in said arm and carrying a frame, independently revoluble stirrers carried by said frame 50 each composed of suitable side pieces or bars and a series of transverse bars extending between the same, a stationary gear concentric with said shaft, and planetary gears upon the axes of said stirrers and arranged to mesh 55 with said stationary gear, substantially as set forth.

In testimony that I claim the foregoing I have hereunto set my hand, at Milwaukee, in the county of Milwaukee and State of Wisconsin, in the presence of two witnesses.

BARTLEY D. McDOWELL.
